UNITED STATES PATENT OFFICE.

HOMER A. GENEST, OF HARTFORD, CONNECTICUT, ASSIGNOR, BY MESNE ASSIGNMENTS, TO UNITED STATES HAT MACHINERY CORPORATION, OF RICHMOND, VIRGINIA, A CORPORATION OF VIRGINIA.

FELT SHRINKING.

Application filed June 25, 1921. Serial No. 480,284.

To all whom it may concern:

Be it known that I, HOMER A. GENEST, a citizen of the United States, residing in Hartford, in the county of Hartford and State of Connecticut, have invented certain new and useful Improvements in Felt Shrinking, of which the following is a specification.

This invention relates principally to the shrinking stage in manufacturing hats or other felt articles.

It is usual to blow the loose fur fibres upon a perforated cone, forming a bat, which is immediately immersed in hot water, thus beginning the shrinking operation and matting and strengthening the bat, which is then usually shrunken by tediously manipulating it in various ways while wet with hot water. This manipulation can be performed only slowly and only by highly skilled artisans, and there is considerable waste of fur.

One of the main objects of the invention is to overcome these objections and shrink the bat expeditiously, by means of operations which can be performed quickly by a lower grade of labor.

In place of the usual kneading process heretofore employed, consisting in repeatedly rolling up the bat in a burlap blanket, and subjecting it to manipulation, and also to the action of pressure rolls, I have contrived to shrink the bat by an improved different method, employing an elastic pad, preferably perforated and preferably in the form of sponge rubber, which is placed upon the bat while the latter is wet with hot water, and this pad is stirred or moved slightly to and fro rapidly while pressed upon the bat, so that the latter, by means of the kneading action so set up, is caused to shrink. As the shrinking proceeds, the kneading strokes are lengthened, and the pressure of the pad upon the bat is increased.

I have found that by applying such an elastic medium to the bat, and vibrating this medium to and fro to a very slight extent, the fur shrinks very rapidly; and if the soft-rubber sheet is made in the form of "sponge rubber" with holes, it felts even more rapidly.

Sponge rubber is highly efficient for this purpose, partly because the rubber, being filled with fine openings, has good effect in 55 locally kneading the bat, and partly because the hot water is repeatedly sucked up by the sponge-rubber pad and forced out again, thereby favoring the kneading action, and also augmenting the effect of the 60 hot water itself upon the bat.

In order to give the pad the aforesaid movements, it may be mounted upon the under side of a board or support, and means may be used to stir or move the device to and fro upon the bat. One of the features of the invention is the provision of power-driven mechanism for this purpose; the board being connected preferably by a pitman to a revolving crank wrist or 70 other power device, whereby minute reciprocations are given to the board and the sponge-rubber pad thereon; provision being made for increasing the length of the stroke as required during the progress of 75 the shrinking. This mechanical operation of the shrinking pad is not limited, however, to the use of sponge or other perforated rubber.

Another feature which may be employed 80 to advantage has reference of the bed upon which the bat to be shrunken is placed; this bed being improved by the use of ruffles extending thereon transversely to the direction of reciprocation of the rubber 85 pad.

Other features and advantages will hereinafter appear.

In the accompanying drawings,

Figure 1 is an elevation, illustrating a 90 bat as it appears after having been removed from the forming cone and immersed in hot water.

Fig. 2 is an edge view of the same.

Figure 3 shows the bat placed upon an 95 improved bed provided with kneading ruffles.

Figure 4 is an edge view of the device as seen at Figure 3.

Figure 5 is a side elevation of the preferred form of apparatus, showing the bat being shrunken therein.

Figure 6 shows by comparison with Figure 3 that the bat has been considerably

UNITED STATES PATENT OFFICE.

WILLIAM A. LORENZ, OF HARTFORD, CONNECTICUT, ASSIGNOR TO UNITED STATES HAT MACHINERY CORPORATION, OF RICHMOND, VIRGINIA, A CORPORATION OF VIRGINIA.

FELT SHRINKING.

Application filed July 1, 1921. Serial No. 481,753.

To all whom it may concern:

Be it known that I, WILLIAM A. LORENZ, a citizen of the United States, residing in Hartford, in the county of Hartford and 5 State of Connecticut, have invented certain new and useful Improvements in Felt Shrinking, of which the following is a specification.

This invention relates to the shrinking 10 of felt for hats and other articles.

In making a hat, it has been the practise to form a conical body of fur fibers by blowing the fibers upon a perforated conical shell, this fiber cone being then removed and dipped in hot water, whereby the material is somewhat shrunken and solidified and made ready to be handled.

It is usual to roll up the bat thus formed, and subject it to the further action of 20 scalding water; this operation having the effect of kneading the fur or felt, and shrinking the same. Many rolling and kneading operations are required, all of which must be slowly and laboriously performed by highly-skilled labor, with considerable waste of fur fibers. In the final 25 stages, the rolled-up bat is subjected to the action of suitable pressure rolls for kneading and shrinking and bringing the felt to 30 its final solidified condition.

One of the main objects of the present invention is to expedite and improve the shrinking of the bat for hats and other articles. To this end, I employ, as a kneading and shrinking agent, an elastic sheet, such as soft vulcanized rubber, having formed or provided thereon numerous closely spaced protuberances or knuckles, said knuckles being preferably molded in 35 integral with the rubber sheet, and being preferably also of soft rubber. In utilizing the invention in one way, the bat, while wet with scalding water, is rolled up in a rubber blanket provided with the aforesaid 40 knuckles, which, at short intervals, press into the body of the bat throughout its area, producing numerous indentations and flexions of the bat, or forcing it into tortuous shape, whereby the vermicular action of the 45 fur fibers is promoted and the shrinking action hastened. While the bat is rolled up in the described blanket, it is subjected to a kneading action corresponding generally 50 to that commonly employed where a burlap

blanket is used. The blanket and bat are 55 unrolled and the operation is repeated, and, from time to time, while unrolled, the bat is opened out and reflattened or folded with the creases in new places, so as to avoid the matting together of the fibers at the creases. 60 Owing to the use of the improved blanket, the shrinking operation is substantially shortened, and a high quality of product is secured.

In order to provide for a maximum flexibility of the blanket, the knuckles thereon, which are preferably of the form of pyramids of little elevation, may be made hollow. In other words, depressions formed upon the under side of the blanket correspond with elevations upon the upper side thereof, so that the blanket is highly flexible throughout, thus increasing and promoting the kneading effect and the vermicular motion of the fibers or shrinking of the bat. 70 75

Other features and advantages will hereinafter appear.

In the accompanying drawings,

Figure 1 shows a bat after it has been removed from the forming cone and dipped in scalding water.

Figure 2 shows an edge view of the same.

Figure 3 shows the preferred form of blanket, the surface of which is divided up into rows of closely-placed pyramids. In practise, such pyramids may be of small proportions, so that relatively great numbers thereof may operate upon the bat shown placed upon the blanket or mat. 85

Figure 4 is a sectional edge elevation 90 taken at about the line 4-4 of Figure 3.

Figure 5 shows the improved blanket or mat rolled up from the Figure 3 position, with one or more bats inside thereof.

Figure 6 is an enlarged perspective detail 95 to show the pyramidal hollows on the under side of the blanket or mat, to render the same more flexible and to provide more points into which the bat may be pressed, thus increasing the kneading capacity of 100 the mat.

The bat 10 is shown in elevation at Figure 1 and in edge view at Figure 2, as collapsed or flattened, its side creases being indicated at 11. It is laid upon a blanket 12, which may consist of the material hereinafter mentioned; the blanket placed upon a bed 13. The end 14 of the blanket is folded 105

of the sheet in registry with said pyramids.

6. A sheet of soft vulcanized rubber having thereon numerous knuckles to form a blanket for kneading a hot, wet, fur bat to shrink the same, said knuckles molded integral with said sheet, and also consisting of soft rubber, said knuckles in the form of pyramids.

7. An elastic rubber blanket having 10 knuckles in the form of pyramids on one side the bases of said pyramids adjoining each other so that they cover the entire working area of said blanket, and provided with recesses at the pyramids on the other 15 side.

8. The process of shrinking a fur bat while wet with scalding water, comprising rolling the bat up in a soft rubber blanket

provided with pyramid knuckles, whose bases adjoin each other so that said knuckles 20 cover practically the entire working area of the blanket, said knuckles, at short intervals, pressing into the body of the bat throughout the same.

9. The process of shrinking a hot, wet, 25 fur bat, comprising kneading the same while it is in contact with numerous soft rubber knuckles tapering towards their tops and flexibly supported upon a soft rubber sheet and having their bases adjoining each 30 other thereby covering practically the entire working area of said sheet.
